3 Claims

ABSTRACT OF THE DISCLOSURE

Sulfoximines having a long chain alkyl group, a short chain alkyl group and an active halogen are useful as antibacterial, antifungal and bleach compounds, particularly in combination with an alkaline builder salt.

BACKGROUND OF THE INVENTION

Organic compounds containing a nitrogen bonded halogen atom are known and used as sterilizing and bleaching materials. Most of the organic molecules containing active halogen are merely carriers for the halogen and serve no other function in a sterilizing or bleaching process. The preferred halo compounds are usually chosen for stability and usefulness solely for the purpose of halogen release in solution.

OBJECTS

It is an object of this invention to provide an organic compound containing a nitrogen-halogen group which is an effective antibacterial, antifungal and bleaching material and which, when hydrolyzed, can also provide surface activity and detergency to an aqueous medium.

SUMMARY OF THE INVENTION

The class of compound of this invention comprises N-halosulfoximines of the following formula:

R' is methyl or ethyl and X is Cl, Br or I. The C₁₀—C₁₄ alkyl, methyl, chloro or bromo compounds are preferred. The compounds of the invention are preferably used with an alkaline salt which provides a pH in aqueous solution of from about 8 to about 12.

DETAILED DESCRIPTION

Unsymmetrical dialkyl sulfoximines having detergent properties are known and described in U.S. Pat. 3,255,116 issued to Jim S. Berry on June 7, 1966. The corresponding N-halosulfoximines can be prepared by halogenating the Berry sulfoximines with a hypochlorite compound, such as NaOCl, NaOBr or NaOI or with elemental halogen such as Cl₂, Br₂ or I₂. Either method of halogenation is under conditions which are conventional for the halogenation of organic compounds containing an NH grouping. Such conventional halogenating conditions preferably involve aqueous solution, temperatures ranging from 0° C. to 50° C., a pH in the range of 10 to 13, agitation, and a quantity of halogen ranging from 1.0 to 5 moles per mole of the compound containing the NH group. An example of halogenation of S,S dimethyl sulfoximine is found in an article by Rolf Appel et al., in *Chemische Berichte*, Jahrg. 99, pages 3108-3117 (1966) entitled "Über die Chloraminierung von Thioäthern."

2

Specific examples of the compounds of this invention include the following:

5 decyl methyl N-chlorosulfoximine,
dodecyl methyl N-chlorosulfoximine,
dodecyl methyl N-bromosulfoximine,
dodecyl methyl N-iodosulfoximine,
tetradearyl methyl N-chlorosulfoximine,
tetradearyl ethyl N-iodosulfoximine,
hexadecyl ethyl N-chlorosulfoximine,
10 dodecyl ethyl N-bromosulfoximine.

The N-halosulfoximines of this invention hydrolyze in aqueous solution to form active halogen which functions for antibacterial, antifungal or bleaching purposes, leaving the sulfoximine molecule as a surface active agent and detergent to facilitate the action of the active halogen as well as providing detergency to the solution being employed for these purposes. Most desirable results are achieved when the N-halosulfoximine is used with a 15 water-soluble alkaline compound which provides a pH in aqueous solutions in the range of about 8 to about 12, preferably in a weight ratio of N-halosulfoximine to alkaline compound ranging from about 5:1 to about 1:20.

The alkaline compounds used with the N-halosulfoximines include both water-soluble inorganic and organic alkaline salts, preferably those salts which act as builder salts. Such builder salts function with the sulfoximine detergent resulting from hydrolysis of the N-halo compound to enhance the detergency characteristics thereof.

Examples of suitable water-soluble, inorganic alkaline detergency builder salts are alkali metal carbonates, borates, phosphates, polyphosphates, bicarbonates, silicates and sulfates. Specific examples of such salts are sodium and potassium tetraborates, perborates, bicarbonates, carbonates, tripolyphosphates, pyrophosphates, orthophosphates and hexametaphosphates.

Examples of suitable organic alkaline detergency builder salts are: (1) Water-soluble aminopolyacetates, e.g., sodium and potassium ethylenediaminetetraacetates, nitrilotriacetates and N-(2-hydroxyethyl)-nitrilo diacetates; (2) Water-soluble salts of phytic acid, e.g., sodium and potassium phytates—see U.S. Pat. 2,739,942; (3) Water-soluble polyphosphonates, including specifically, sodium, potassium and lithium salts of ethane-1-hydroxy-1,1-diphosphonic acid, sodium, potassium and lithium salts of methylene diphosphonic acid, sodium, potassium and lithium salts of ethylene diphosphonic acid, and sodium, potassium and lithium salts of ethane-1, 1,2-tri-phosphonic acid. Other examples include these alkali metal salts of ethane-2-carboxy-1,1-diphosphonic acid, hydroxy-methanediphosphonic acid, carbonyldiphosphonic acid, ethane-1-hydroxy-1,1,2-tri-phosphonic acid, ethane-2-hydroxy-1,1,2-tri-phosphonic acid, propane-1,1,3,3-tetraphosphonic acid, propane-1,1,2,3-tetraphosphonic acid, and propane-1,2,2,3-tetraphosphonic acid; (4) Water-soluble salts of polycarboxylate polymers and copolymers as described in the patent of Francis L. Diehl, U.S. 3,308,067 issued Mar. 7, 1967. Specifically, a detergent builder material comprising a water-soluble salt of a polymeric aliphatic polycarboxylic acid having the following structural relationships as to the position of the carboxylate groups and possessing the following prescribed physical characteristics: (a) a minimum molecular weight of about 350 calculated as to the acid form; (b) an equivalent weight of about 50 to about 80 calculated as to acid form; (c) at least 45 mole percent of the monomeric species having at least two carboxyl radicals separated from each other by not more than two carbon atoms; (d) the site of attachment to the polymer chain of any carboxy-containing radical being separated by not more than three carbon

atoms along the polymer chain from the site of attachment of the next carbonyl-containing radical. Specific examples are polymers of itaconic acid, aconitic acid, maleic acid, mesaconic acid, fumaric acid, methylene malonic acid, and citraconic acid and copolymers with themselves and other compatible monomers such as ethylene.

Mixtures of organic and/or inorganic builders can be used and are generally desirable. One such mixture of builders is disclosed in Canadian Pat. 755,038 of Burton H. Gedge, e.g., ternary mixtures of sodium tripolyphosphate, trisodium nitrilotriacetate and trisodium ethane-1-hydroxy-1,1-diphosphonate. The above described builders can also be utilized singly in this invention.

The preferred builder salts are sodium tripolyphosphate and sodium nitrilotriacetate, alone or in admixture.

The compositions of this invention can contain, if desired, in addition to the N-halosulfoximine and alkaline salt, any of the usual additives which make them more attractive or effective. For example, perfumes, dyes, proteolytic enzymes, corrosion inhibitors, other chlorine bleaches, soil antiredeposition agents and optical brighteners can be used. The compositions can also contain other organic detergents of the following classes: water-soluble fatty acid soaps; anionic synthetic non-soap detergents; nonionic synthetic detergents of the ethoxylate or semipolar type; zwitterionic synthetic detergents; amphoteric synthetic detergents.

The compounds and compositions of this invention are described in the following examples which are illustrative thereof but are not limiting.

EXAMPLE I

Preparation of decyl methyl N-chlorosulfoximine

Decyl methyl sulfoximine (4.0 g. or 0.0182 mole), M.P. 50-52° C. was suspended in about 40 ml. water and to it was added, with vigorous shaking, 50 ml. 5.25% aqueous sodium hypochlorite (Clorox). After about three minutes shaking at 25° C., the insoluble product was harvested by filtration, air-dried, and recrystallized from hexane to give a white product melting at 50-51° C.

For analytical purposes the product when mixed with the starting sulfoximine gave a mixed melting point depression to 35-37° C. Furthermore, while the infrared spectrum of the product was generally similar to the starting sulfoximine, the sharp, fairly intense N—H stretching absorption at 3.05 μ seen in the sulfoximine was missing in the N-chloro derivative. Analyses on the product gave percent N=5.4 (calc., 5.5); percent S=13.1 (calc., 12.6); and percent Cl=13.4 (calc., 14.0).

EXAMPLE II

Preparation of decyl methyl N-bromosulfoximine

A solution of aqueous sodium hypobromite was prepared by chilling 200 ml. of 1.0 N aqueous sodium hydroxide to 0.5° C. and adding 16.0 g. (0.1 mole) bromine dropwise with stirring. The cold solution was stirred until homogeneous. To a suspension of 4.0 g. of decyl methyl sulfoximine in 40 ml. water was added 75 ml. of the cold, aqueous sodium hypobromite solution prepared above. After three minutes vigorous shaking, the product was harvested by filtration, air-dried, and recrystallized from hexane.

The yellow-colored product melted at 48-50° C.; a mixed melting point with the starting sulfoximine was depressed to 37-39° C. Infrared spectra of the product showed no N—H stretching absorption at 3.05 μ characteristic of the starting sulfoximine.

The procedure of Example I was used to prepare tetradecyl methyl N-chlorosulfoximine by using tetradecyl methyl sulfoximine instead of the decyl compound. Decyl methyl N-iodosulfoximine was made by the procedure of Example II by substituting iodine for bromine.

EXAMPLE III

Preparation of dodecyl methyl N-bromosulfoximine

Dodecyl methyl sulfoximine in 1,2-dimethoxyethane (monoglyme) solvent was reacted with a molar equivalent of sodium hydride (stirred three-neck flask protected from air with nitrogen) to form dodecyl methyl N-sodium-sulfoximine. One molar equivalent of bromine was added slowly, with stirring, to the solution. Removal of the precipitated sodium bromide by filtration gave a solution in monoglyme of dodecyl methyl N-bromosulfoximine.

EXAMPLE IV

Bactericidal evaluation of tetradecylmethyl N-chlorosulfoximine was made by the following procedure

Test solutions: Cidal tests were carried out in FDA broth. Organisms: One ml. of a 24-hour culture of *Staphylococcus aureus* and *Escherichia coli* containing approximately 250 x 10⁶ organisms per ml. was used as the inoculum.

Media: FDA broth (5 g. Bacto Beef Extract, 10 g. Bacto Peptone, 5G C.P. grade NaCl in 1,000 ml. distilled water). Difco Nutrient Agar was employed.

Procedure:

(a) To tubes containing the tetradecyl methyl N-chlorosulfoximine at a concentration of 100 p.p.m. in FDA broth was added 1 ml. of a 24-hour culture of the organism and these were shaken thoroughly and placed in a water bath at 37° C.

(b) A 1 ml. transfer from a tube indicated in (a) was made after 10 minutes of contact of the organism with the N-halosulfoximine into 100 ml. of 5% sterile horse serum in distilled water. Additional dilutions were made from the horse serum so that the number of colonies per plate fell in a countable range. Dilutions also served to counteract possible static effects of the additive carried over in the original transfer. The dilutions were plated in nutrient agar.

(c) After 48 hours of incubation at 37° C., plates were counted and the results expressed as percent kill.

(d) Controls were run in the matrix as well as in distilled water.

At 100 p.p.m., methyl tetradecyl N-chlorosulfoximine gave 99.9% kill of *S. aureus* and 99% kill of *E. coli*.

EXAMPLE V

Determination of fungicidal and fungistatic activity of decyl methyl N-halosulfoximines

A spore suspension (1.0 ml.) of *Microsporum gypseum* was used to inoculate petri plates containing from 15 to 20 ml. of Sabouraud's Dextrose Broth (Difco) and the plates were subsequently incubated at 25° C. for two weeks. This period of incubation allowed the organism to grow over the entire surface of the broth, thus forming a tough mycelial mat. This mycelial mat was then cut by means of a sterile cork borer (12 mm. diameter) into "mycelial plugs."

Fungicidal activity was determined by immersing the plugs into 100 ml. of a solution of the N-halosulfoximine compounds for various lengths of time. The mycelium was kept submerged by agitating the solution with a magnetic stirrer. At 0, 5, 10, 20, 30 and 60 minutes after initiation of the test, mycelial plugs were removed and given two rinses, each of approximately five minutes' duration, in 100 ml. of sterile distilled water. The washed mycelial plugs were plated onto Sabouraud's Dextrose Agar (Difco) and observed periodically for growth. If no growth was observed from a given mycelial plug after seven days of incubation at 25° C., the organism was considered to have been killed by the experimental material in the time interval indicated. Fungicidal activities were measured using this procedure with decyl methyl N-chloro- and

5

N-bromosulfoximines. Both compounds killed the organism, *M. Gypseum*, upon exposures between 30 and 60 minutes.

Fungistatic activity was determined by the agar incorporation method. The experimental material was incorporated into Sabouraud's Dextrose Agar at 100 and 1,000 p.p.m. after the agar had been sterilized and cooled to 45° C. The agar was then poured into plates and inoculated with "mycelial plugs" (described above) and incubated for 14 days at 25° C. At that time the concentration required to prevent growth of the fungus was ascertained. Both decyl methyl N-chloro and N-bromo-sulfoximines exhibited fungistatic activity at 1,000 p.p.m.

COMPOSITION EXAMPLES

Alkaline compositions having the following formulations and pH's ranging from 8 to 12 can be prepared with the N-halosulfoximines of this invention incorporated to therein. In solution the N-halosulfoximines hydrolyze to provide active chlorine and detergency. The compositions impart effective antibacterial and antifungal action on fabrics cleansed in solutions of the composition as well as cleansing and bleaching the fabrics.

EXAMPLE VI

	Percent
Dodecyl methyl N-chlorosulfoximine	20
Sodium tripolyphosphate	50
Sodium sulfate	30

EXAMPLE VII

	Percent
Tetradecyl methyl N-bromosulfoximine	10
Condensation product of 11 moles of ethylene oxide with 1 mole of coconut fatty alcohol	10
Trisodium nitrilotriacetate	10
Sodium tripolyphosphate	60
Sodium silicate	10

A water solution containing 0.15%, 0.3% and 0.45% concentrations of the above formula provides antibacterial, antifungal and stain removal results in household laundering of fabrics.

EXAMPLE VIII

The following granular laundry composition containing an effective chlorine bleaching agent performs very well in cleaning, whitening and antibacterial activity.

	Percent
Tetradecyl methyl N-chlorosulfoximine	7
Sodium linear dodecylbenzenesulfonate	17
Sodium tripolyphosphate	50
Sodium carbonate	10
Sodium sulfate	10
Moisture	Balance

6

EXAMPLE IX

Another chlorine bleach composition according to this invention suitable for bleaching stained cotton fabrics has the following composition:

	Percent
Decyl methyl N-chlorosulfoximine	20
Trisodium ethane-1-hydroxy-1,1-diphosphonate	40
Trisodium nitrilotriacetate	40

EXAMPLE X

An antibacterial laundry detergent has the following formula:

	Percent
Sodium linear dodecylbenzenesulfonate	10
Sodium tallow alkyl sulfate	5
Sodium tripolyphosphate	30
Trisodium nitrilotriacetate	20
Sodium silicate (ratio SiO ₂ :Na ₂ O of 2:1)	10
Sodium sulfate	15
Decyl methyl N-iodosulfoximine	10

The foregoing description of the invention has been presented describing certain operable and preferred embodiments. It is not intended that the invention should be limited since variations and modifications thereof will be obvious to those skilled in the art, all of which are within the spirit and scope of this invention:

What is claimed is:

1. N-halosulfoximine of the following formula:

wherein R is an alkyl group containing 10 to 16 carbon atoms, R' is methyl or ethyl and X is Cl, Br or I.

2. The sulfoximine of claim 1 wherein R is decyl, dodecyl or tetradecyl, R' is methyl and X is Cl or Br.

3. The sulfoximine of claim 2 wherein X is Cl.
